RADIATOR HOOD

Albert H. Levene, Newark, N. J.

Application November 25, 1929
Serial No. 409,500

6 Claims. (Cl. 237—78)

This invention relates to hoods for use in connection with radiators of various kinds and classes, for the purpose of deflecting the heat rising therefrom and further to form a shelf or support upon which various articles may be placed; and the object of the invention is to provide a device of the class specified, the hood of which consists of telescoping parts whereby the same may be mounted upon radiators of different length, the width of said telescoping parts being such as to adapt the same for use on substantially any size and style of radiator, which is in conventional use; a further object being to provide a simple and yet strong and durable means for coupling the hood with the radiator in such manner that the hood can safely support any articles placed thereon and also to provide a space between the top of the radiator coils and the top of said hood; a further object being to arrange within the space formed in the hood, a pan in which water may be placed to maintain as near as possible, a moist rather than dry atmospheric condition; a still further object being to provide means arranged in one part of the hood and adapted to enter said pan to provide for the filling and refilling thereof and to act as a gage to indicate the level of water in the pan; and with these and other objects in view, the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

40 Fig. 1 is a longitudinal sectional view through my improved hood illustrating the manner of coupling the same with the end coils of a radiator.

Fig. 2 is a partial section on the line 2—2 of Fig. 1.

45 Fig. 3 is a section on the line 3—3 of Fig. 1; and,

Fig. 4 is a sectional detail view showing a modification.

In the drawing 5 represents the coils of a radiator of any kind or class, the upper ends of the separate coils being placed in communication by couplings 6 which bridge said coils. In practice, I provide a hood consisting of two parts 7 and 8 which are U-shaped in cross sectional form, the part 8 being arranged over the part 7 and the latter part telescoping with the part 8 so that the end wall 9 of the part 7 may be moved relatively to the end wall 10 of the part 8.

The side wall 11 of the part 8 has a downwardly extending and angularly disposed deflec-

tor 12 terminating in a flange 13 folded inwardly upon the deflector. The corresponding wall 14 of the part 7 is also provided with a deflector 15, the lower end of which rests in and is guided by the flange 13 in the telescoping movement of 65 the parts.

The other side wall 16 of the part 8 terminates in an inwardly and upwardly directed flange 17 in which the lower edge of the side wall 18 of the part 7 operates, thus retaining the parts 7 and 8 70 against displacement in their telescoping movement.

The end wall 9 of the part 7 has an extension 9a folded inwardly upon the inner face of said wall, which extension terminates below the top 75 wall of the part 7 in an inwardly directed flange 9b which forms a lock member to retain the part against displacement as later described. The end wall 10 is of similar construction and has the extension 10a terminating in the flange or lock 80 member 10b.

I also employ two mounting plates 19, which are of similar construction and the brief description of one will apply to the other. The plate 19 is provided at its outer end with an upwardly 85 extending flange 20 which is normally arranged adjacent the end walls 9—10 of the hood when mounted in position as clearly seen in Figs. 1 and 2 of the drawing. This plate is adapted to rest upon two or more of the coils 5 of the radiator 90 as seen in Fig. 1 and is provided at a predetermined distance from the flange 20 with two elongated apertures 21 arranged adjacent the sides of said plate, the apertures being preferably in alignment and parallel to the flange 20 as shown. 95

In coupling the plates 19 with the radiator, I provide a transverse bar 22, the ends of which have threaded holes to receive coupling rods 23 or the threaded end portions 24 thereof, the upper ends of said rods having elongated loop-shaped heads 25 by means of which the rods may be rotated in adjustably clamping the plates 19 in position. It will be understood that the rods 23 will be coupled with the ends of the bar 22 and when so coupled, the entire unit will be placed between two of the coils of the radiator beneath the bridge couplings 6 and so as to extend the heads 25 above the coils, after which the plates 19 are mounted in position by passing the heads 25 of the rods 23 through the elongated apertures 21 and then rotating said rods to draw the bar or bars 22 upwardly and the plates 19 downwardly. The plates 19 are clamped in position in such manner as to arrange the flanges 20 outwardly with respect to the outer faces of the end coils of the radiator, and when secured in position an elongated water pan 26 is placed upon the plates 19 and arranged between the heads 25 110 of the rods 23 and preferably is of such length as to extend to a point adjacent each of the flanges 115 120

20 in the manner seen in Fig. 1 of the drawing; and the hood may now be placed in position. In this operation, the parts 7 and 8 are separated to a sufficient degree to permit the free placement of the part 8 upon the adjacent plate 19, it being understood that the flange 10b is passed beneath said plate as clearly seen in Fig. 1, so as to lock the part 8 against displacement from the radiator, after which the part 7 is moved inwardly to bring the flange 9b thereof beneath the plate 19 at the other end of the radiator, the part 8 being held against movement in this operation.

15 The top wall of the part 8 is provided adjacent the end wall 10 with an aperture in which is mounted a cup-shaped filling cup and gage device 27 which extends well within the pan 26. This cup facilitates the filling of the pan and also serves as a gage to indicate the level of water 20 therein. By means of this device, the water in the pan may be maintained at a proper level at all times without removing the hood from the radiator.

25 In order that the two parts 7 and 8 may be telescoped toward each other to the greatest degree, the inner end of the top wall of the part 7 has an elongated aperture 28 sufficiently large to clear the cup 27. It is also preferred that clearance be provided between the flange 10b and 30 the adjacent side walls 11 and 16 as seen at 29, note Figs. 2 and 3, to permit the side walls 14 and 18 to move to a point adjacent the end wall 10 of the part 8.

35 From the foregoing, it will be apparent that my improved radiator hood may be applicable to a large range in size of radiators, thus eliminating the difficulty of manufacturing these devices in many fixed sizes. By virtue of the simplicity in the structure of the hood and the manner of 40 its coupling with the radiator, the same may be retailed at a comparatively low selling price to bring the same within the reach of all classes of people.

45 In Fig. 4 of the drawing, I have shown a slight modification wherein a mounting plate 19a is mounted upon and coupled with the coils 5a of a radiator by coupling rods 23a similar to the rods 23, the plate having an upwardly extending flange 20a which differs from the flange 20 in that it 50 has a horizontally and laterally extending part 20b having one or more threaded holes 20c to receive machine screws 30 for securing the slab 31 to the mounting plate 19a and to arrange the same above and in spaced relation to the top of 55 the coils 5a. The slab 31 may be composed of any suitable material such for example as wood, marble, metal or the like. While this slab forms a hood and shelf member, it does not necessarily include side wall members.

60 I preferably arrange upon the pan 26 a yoke-shaped spacing member 26a located centrally of the hood and which serves to support and reinforce the top walls 7 and 8 of the hood, and it will be understood that two or more of these devices may be employed if desired.

65 It will be understood that the hood may be painted or otherwise treated to produce the same in any desired colors or color effects to render the device neat and ornamental in appearance.

70 It will also be understood that by providing comparatively long coupling rods and comparatively long threaded end portions thereon, the plates 19 may be coupled with radiators of any style or construction, and this attachment may 75 be made without the use of tools of any kind.

It will be understood that my invention is not necessarily limited to the specific details of construction of the several parts nor to the specific arrangement of said parts herein shown, and various changes therein and modifications thereof may be made within the scope of the appended claims without departing from the spirit of my invention or sacrificing its advantages.

Having fully described my invention, what I claim as new and desire to secure by Letters Patent, is:—

1. A radiator cover adapted to be mounted over a radiator and above a water receptacle supported on said radiator adjacent the end portions thereof, said cover comprising telescoping parts, 90 a cup-shaped body having an opening in the bottom, said body being mounted in one of said parts adjacent the outer end thereof and projecting from the lower surface thereof and into the water receptacle mounted on the radiator to 95 form a filler and gage device for the receptacle.

2. A radiator cover adapted to be mounted over a radiator and above a water receptacle supported on said radiator adjacent the end portions thereof, said cover comprising telescoping parts, 100 a cup-shaped body having an opening in the bottom, said body being mounted in one of said parts adjacent the outer end thereof and projecting from the lower surface thereof and into the water receptacle mounted on the radiator 105 to form a filler and gage device for the receptacle, and the telescoping part adjacent said first named part having a recessed end wall to receive said cup-shaped body when said parts are telescoped together.

3. A radiator cover adapted to be arranged over a radiator and above a water receptacle supported on said radiator, said cover comprising telescoping parts including top and side walls to adapt the cover to radiators of different lengths, 115 one part of the cover having a cup-shaped body with an opening in the bottom wall thereof, said body projecting from the lower surface of said part into the water receptacle mounted on the radiator to form a filling and gage device for said 120 receptacle, and means at spaced intervals on the radiator and on the side walls of the cover for retaining the cover against accidental displacement from the radiator.

4. A cover adapted to be mounted on a heating 125 unit and above a water receptacle supported on said unit, a cup-shaped body in said cover, the lower end portion of which has an opening, said body projecting from the lower surface of the cover and into said water receptacle to form a 130 filler and water gage device for said receptacle.

5. A cover adapted to be mounted on a heating unit and above a water receptacle supported on said unit, a cup-shaped body in said cover, the lower end portion of which has an opening, said 135 body projecting from the lower surface of the cover and into said water receptacle to form a filler and water gage device for said receptacle, and means for retaining the cover against displacement from said heating unit.

6. A cover for mounting on a heating unit and above a water receptacle on said unit, said cover comprising telescoping parts, a cup-shaped body in one of said parts, the lower portion of which includes an opening, and said body projecting 145 from the lower surface of said cover part and into the water receptacle to a point adjacent the bottom of the receptacle to form a filler and water gage device for said receptacle.
